UNITED STATES PATENT OFFICE.

ANDREW M. LACKEY, OF BROWNSBURG, VIRGINIA, ASSIGNEE TO JAMES A. PORTER AND JAMES H. CHAMBERS, OF MACE, INDIANA.

CUTTER-BAR FOR MOWERS AND REAPERS.

SPECIFICATION forming part of Letters Patent No. 255,387, dated March 21, 1882.

Application filed May 17, 1881. (No model.)

To all whom it may concern:

Be it known that I, ANDREW M. LACKEY, of Brownsburg, in the county of Rockbridge and State of Virginia, have invented a new and useful Improvement in Cutter-Bars for Mowers and Reapers, of which the following is a full, clear, and exact description.

Figure 1 is a front elevation of my improvement, the sickles being removed. Fig. 2 is a plan view of the improvement, the cap-plate being removed. Fig. 3 is a sectional elevation of the same, taken through the line *x x*, Fig. 2. Fig. 4 is a plan view of one of the sickles. Fig. 5 is a cross-section through the cutter-bar and its cap-plate, showing an edge view of a sickle. Fig. 6 is an edge view of a portion of the locking-bar having the screw formed on it. Fig. 7 is a perspective view of one of the sickles.

The object of this invention is to facilitate the attachment and removal of cutter-bar sickles.

A represents the cutter-bar, upon the upper side of which are formed dovetailed cross-grooves to receive the dovetailed shanks *C* of the sickles *B*. Upon the sides of the sickles *B*, at the ends of their cutting-edges, are formed square edges *D*, which abut against each other, as shown in Fig. 2, to strengthen the said sickles against lateral movement.

*In one side of the shanks *C* of the sickles *B* are formed notches or square recesses *E*, to receive the locking-blocks *F*, formed upon or attached to the dovetailed bar *G*, which slides in a dovetailed groove in the cutter-bar *A*, so as to be beneath the shanks *C* of the sickles *B*. The locking-blocks *F* are made of such a shape and size as to correspond with the projecting parts of the cutter-bar *A*, at the opposite sides of its cross-grooves. With this construction, when the sliding bar *G* is pushed outward the locking-blocks *F* correspond in position with the projecting parts of the cutter-bar *A*, and the sickles *B* are released, so that any or all of the said sickles can be easily withdrawn to replace a broken sickle with a new one and for convenience in grinding the said sickles. The inner end of the sliding bar *G* projects and has a screw-thread cut upon it to receive a nut, *H*, so that the said sliding bar *G* can be drawn inward to bring the locking-*

blocks *F* into the notches *E* by screwing up the said nut *H*, locking the sickles *B* securely in place. The sickles *B* are unlocked by loosening the nut *H* and pushing the sliding bar *G* outward.

The shanks *C* of the sickles *B* and the locking-blocks *F* of the sliding bar *G* are covered and protected by a cap-plate, *I*, which is securely riveted to the cutter-bar *A*, between the shanks *C* of the sickles *B*.

It will be seen by reference to Figs. 4 and 7 that the edges *a b b* of the sickle-shanks are beveled and form, in connection with the dovetail tenons on the bar *A*, interlocking dovetail attachments for the sickles. It will also be seen that the longitudinal edges *c* of the square recesses *E* are also beveled to allow the correspondingly-beveled edges *d* of the blocks *F* to overlap them, and thus aid materially in holding the sickles rigidly in their places. By thus constructing the parts the bar *G* not only prevents the sickles from being drawn out of their grooves in bar *A*, but the bar *G* also operates, when forced home by screwing up nut *H*, to draw or wedge down the shanks of the sickles upon the floors of their grooves in bar *A*. In a practical point of view this feature of locking the sickle-shanks down on bar *A* by means of the sliding bar *G* is a very important one in connection with the dovetail attachments of the sickle-shanks to said bar *A*. The attachment is very substantial and great rigidity is effected. The cap-plate *I* can be made much thinner, and consequently lighter, than without such locking attachment. The beveled edges *f*, opposite the beveled edges *d* of blocks *F*, will allow the sickles to be readily removed when bar *G* is adjusted so that blocks *F* are out of the notches *E* in the sickle-shanks.

I do not claim as my invention dovetail sickle-shanks adapted to enter corresponding grooves in the sickle-bar, said shanks being also notched to receive blocks on a sliding bar, as such a combination, broadly considered, is found in Letters Patent No. 90,086, of 1869.

The pitman-eye *J* can be attached to the inner end of the cap-plate *I*, as shown in Fig. 1, or to the middle part of the said plate, as shown in Fig. 3, as the construction of the machine may require.

It will be seen that by my improved construction the blocks on bar G serve two purposes, viz: They enter the notches E and prevent the sickles from being drawn out of their places, and they act like wedge bearings on the bevels c of the sickle-shanks to allow the sickles to be tightened when they become loose. By setting up the nut H the blocks draw down upon the sickle-shanks with great force and reset the sickles.

Having thus fully described my invention,

what I claim as new, and desire to secure by Letters Patent, is—

The combination of the sickle-sections having notched dovetail shanks, the notches E being beveled at c, the bar G, having beveled blocks F, adapted to ride up on bevels c, and the adjusting-nut H, substantially as described.

ANDREW M. LACKEY.
